UNITED STATES PATENT OFFICE.

THOMAS F. MORRIN, JR., OF JERSEY CITY, NEW JERSEY, ADMINISTRATOR OF
THOMAS F. MORRIN, DECEASED.

STEAM-BOILER.

950,296.

Specification of Letters Patent. Patented Feb. 22, 1910.

Application filed June 12, 1908. Serial No. 438,084.

To all whom it may concern:

Be it known that THOMAS F. MORRIN, deceased, in his lifetime a resident of Jersey City, in the county of Hudson and State of New Jersey, and a citizen of the United States, previous to his death had invented certain new and useful Improvements in Steam-Boilers, of which I, THOMAS F. MORRIN, Jr., a resident of Jersey City, in the county of Hudson and State of New Jersey, and a citizen of the United States, as administrator of the estate of said THOMAS F. MORRIN, present the following full, clear, and exact specification.

15 This invention relates to steam boilers and has for its object to improve the construction of such boilers and to provide an increased heating surface, whereby the rapid economical generation of steam may be facilitated

20 and the invention is illustrated in the accompanying drawings therein.

Figure 1 is a front elevation with part of the casing broken away and parts shown in section of the improved boiler. Fig. 2 is a 25 side elevation with part of the casing broken away. Fig. 3 is a plan view of the same. Fig. 4 is a front elevation with part of the casing removed and parts shown in section of a modified construction. Fig. 5 is a side 30 elevation of said modification with part of the casing broken away and Fig. 6 is a plan view of the same with part of the casing removed and parts shown in section.

The invention as illustrated is embodied 35 in a water tube boiler but is applicable as well to other species of boilers.

The grate 1 is of usual construction and the boiler is provided with the usual fuel doors 2 and ash pit doors 3. The steam 40 drum 4 is provided with a tube sheet 5 which is of the shape of a somewhat flattened V and each side of said tube sheet receives transversely inclined tubes, which are arranged in two sets 6, 7, and at their lower 45 ends are received in tube sheets 8, 9 of manifolds 10, 11. These tube sheets are parallel with the corresponding faces of tube sheet 5. A baffle plate 12 is arranged vertically 50 among the tubes 6, 7, and two spaces are left between the baffle plate and the casing at the

front and rear edges of the baffle plate for the free passage of the gases of combustion. These baffle plates serve to cause the flame to pass by a circuitous route through all the tubes. Blow off pipes 13, 14, are connected 55 to manifolds 10, 11 respectively.

In Figs. 1, 2 and 3, the longitudinally inclined tubes are arranged in three sets or groups, of which two are shown in Fig. 2 and are designated 15, 16 and the said three 60 groups of tubes are connected to front headers 17, 18, 19 and rear headers 20, 21, and 22. Circulation pipes 23, 24 and 25, connect the headers 17, 18 and 19 with each other and with the steam drum. A feed water pipe 26 65 is connected to manifolds 10 and 11 and to the rear headers 21, 22. The side casing 27 extends from front to rear of the boiler and is closed at the top by angle irons 28, or other suitable material and these angle irons 70 close the space between the said casing and the steam drum, on both sides of the flue 29, being omitted within the flue.

In Figs. 4, 5 and 6, the boiler is somewhat 75 smaller and the two lower groups of longitudinally inclined pipes and their headers are omitted and but one group 15 of such pipes is employed, connected to headers 17 and 20, which are connected by circulation pipes 25 to the steam drum. The construction in 80 other respects is in substance the same as that of Figs. 1, 2 and 3.

What is claimed is:

A steam boiler comprising a steam drum, a plurality of manifold chambers, a plurality 85 of groups of transversely inclined tubes connecting said drum and manifolds, an inclined baffle plate disposed intermediate each of said groups extending between said drums and manifolds having free spaces at its 90 edges, a plurality of longitudinally inclined tubes disposed between said groups and headers connecting said last named tubes.

THOMAS F. MORRIN, JR.,
Administrator of the estate of Thomas F.
Morrin, deceased.
